G. W. COMER.
ELECTRICAL SIGNALING DEVICE.
APPLICATION FILED OCT. 19, 1915.

1,229,035.

Patented June 5, 1917.

UNITED STATES PATENT OFFICE.

GUY W. COMER, OF CHICAGO, ILLINOIS, ASSIGNOR TO AUTO-SIGNAL CO., OF CHICAGO, ILLINOIS, A CORPORATION OF ILLINOIS.

ELECTRICAL SIGNALING DEVICE.

1,229,035.

Specification of Letters Patent.

Patented June 5, 1917.

Application filed October 18, 1915. Serial No. 56,720.

To all whom it may concern:

Be it known that I, GUY W. COMER, a citizen of the United States, and a resident of the city of Chicago, county of Cook, and State of Illinois, have invented certain new and useful Improvements in Electrical Signaling Devices, of which the following is a specification.

My invention relates to improvements in electrical signaling devices for vehicles, and has for its object, the production of a device of this character which will be of simple construction and efficient in use.

Other objects will appear hereinafter.

The invention consists in the combinations and arrangements of parts hereinafter described and claimed.

The invention will be best understood by reference to the accompanying drawing forming a part of this specification, and in which,

Fig. 1 is a central longitudinal section through a signaling device embodying the invention,

Fig. 2 is a rear elevation thereof shown partly in section, and

Fig. 3 is a section taken on line $x-x$ of Fig. 1.

The preferred form of construction, as illustrated in the drawing, comprises a bracket or supporting arm 1 adapted, when the device is in use, for mounting upon the vehicle in connection with which the device is employed. Fastened in the outer end of bracket 1 is a laterally projecting tube 2 upon which is rotatably mounted a sleeve 3.

Fixed to the sleeve 3 is a signaling arm 4 consisting of a front plate 4' and a rear plate 4'', said arm being fastened to an annular outwardly projecting flange 5 formed upon the sleeve 3 by means of bolts 6 and cooperating nuts 7. The arrangement is such, as will be seen, that free oscillation of the signaling arm is permitted upon the tube 2. No means for effecting such oscillation is disclosed in this case, such construction being embodied in another pending application.

The parts 4' and 4'' of the arm 4 are connected together by flanges 8 formed at the longitudinal edges of the part 4'' which embrace the corresponding edges of the part 4'. The parts 4' and 4'' are of tapered formation so that, upon rearward sliding of the part 4'', the flanges 8 will disengage

from the corresponding edges of part 4' and thus permit of removal of the part 4'' so as to allow access being gained to the interior of the arm. The part 4'' is provided at its rearward end with a flange 9 and the part 4' is provided at its outer edge with a flange 10 which serve as stops to limit the movement of the part 4'' in sliding the same to position upon the part 4'.

The part 4' adjacent the outer end thereof is formed with an opening over which is arranged a lens 11 held in position by an annular holder 12. Arranged within the arm behind the lens 11 is an electric lamp 13 mounted in a socket 14 fastened to the rearward side of arm member 4'.

Fixed to the end of tube 2 within the signaling arm is a disk 15 of insulating material, said disk being secured to said tube by diametric pins, as shown, and also by a nut 16 threaded upon said tube. Mounted upon the periphery of the member 15 are diametric contact plates 17 having inwardly projecting ears, as shown, secured to the side of member 15 by means of screws 18. The screws 18 serve also as binding posts for connecting the contact members 17 with the feed wires 19 which extend through the opening through tube 2.

Cooperating with the contacts 17 are elongated movable contacts 20, corresponding ends of which are secured by screws 21 to a block 22 of insulating material mounted upon the rearward side of arm member 4'. The screws 21 serve also as binding posts for connection with the conductor wires 23 leading to the lamp socket 14. The contact members 20 are so positioned that the free ends thereof are adapted for engagement against the periphery of the holder member 15, a helical tension spring 24 co-operating with the contact members 20 for normally pressing the same into engagement with said holder periphery. With this arrangement, it will be seen that when the signaling arm is so positioned that the movable contacts 20 engage with the stationary contacts 17, the circuit of lamp 13 will be closed, and when said arm is moved to carry the contacts 20 out of engagement with the contacts 17, said lamp circuit will be broken. In practice, the stationary contact members 17 are so positioned that this engagement of the same by the movable contact members 20 will occur when the sig-

2

naling arm is in horizontal or signaling position. This being so, it will be seen that when the arm is in lowered or non-signaling position, the lamp circuit will be broken and, when said arm is rocked to signaling position, the lamp circuit will be automatically closed in order to light the lamp so as to be visible through lens 11. The make-and-break construction employed is especially advantageous for the purpose inasmuch as with this arrangement the feed wires 19 always remain stationary, there being no bending of the same with the movement of the signaling arm. Also the employment of a tubular supporting element coöperating with the bracket affords an economical and advantageous arrangement inasmuch as it permits of passage of the feed wires to the interior of the signaling arm.

20 While I have illustrated and described the preferred form of construction for carrying my invention into effect, this is capable of variation and modification without departing from the spirit of the invention.

25 I, therefore, do not wish to be limited to the precise details of construction set forth, but desire to avail myself of such variations and modifications as come within the scope of the appended claims.

30 Having described my invention what I claim as new and desire to secure by Letters Patent is:

1. A device of the class described comprising a bracket; a signaling member rockingly supported by said bracket; an electric lamp carried by said signaling member; a make-and-break device for controlling the lamp circuit whereby the lamp circuit will be broken except when the signaling member is in signaling position, said device comprising a circular holder of insulating material fixed to said bracket; a pair of stationary contacts mounted on the periphery of said holder at opposite sides thereof; and a pair 40 of elongated movable contacts fixed at corresponding ends to said signaling member, the opposite ends of said last mentioned contacts being adapted for engagement with the periphery of said holder for contact with said stationary contacts when said signaling member is in signaling position, substantially as described.

45 2. A device of the class described comprising a bracket; a signaling member rockingly supported by said bracket; an electric lamp carried by said signaling member; a make-and-break device for controlling the lamp circuit whereby the lamp circuit will be broken except when the signaling member is in signaling position, said device comprising a circular holder of insulating material fixed to said bracket;

50 a pair of stationary contacts mounted on the periphery of said holder at opposite sides thereof; and a pair of elongated movable contacts fixed at corresponding ends to said signaling member, the opposite ends of said last mentioned contacts being adapted for engagement with the periphery of said holder for contact with said stationary contacts when said signaling member is in signaling position, substantially as described.

55 3. A device of the class described comprising a bracket; a laterally projecting tube mounted in said bracket; a signaling arm rockingly mounted on said tube; an electric lamp carried by said signaling arm; a make-and-break device for controlling the lamp circuit whereby the lamp circuit will be broken except when said signaling arm is in signaling position, said device comprising a circular holder of insulating material fixed to said tube; stationary contacts on the periphery of said holder upon opposite sides thereof; and movable contacts carried by said arm engaging against the periphery of said holder and adapted for engagement with said stationary contacts when said arm is in signaling position, substantially as described.

60 4. A device of the class described comprising a bracket; a laterally projecting tube mounted in said bracket through which electrical feed wires are adapted to pass; a signaling arm rockingly mounted on said tube and inclosing the outer end thereof; an electric lamp carried by said signaling arm; a make-and-break device for controlling the lamp circuit whereby the lamp circuit will be broken except when the signaling arm is in signaling position, said device comprising a circular holder of insulating material fixed to said tube; stationary contacts angularly disposed with relation to each other on the periphery of said holder with which said feed wires are connected; and movable contacts carried by said arm with which the lamp conductor wires engage, said movable contacts engaging against the periphery of said holder for contact with said stationary contacts when said signaling arm is in signaling position, substantially as described.

65 In testimony whereof I have signed my name to this specification in the presence of two subscribing witnesses.
